MOTION PICTURE PROJECTOR CONTROL

Charles Woodruff, New York, N.Y., assignor to Port-A-Films Presentations, Inc., New York, N.Y., a corporation of New York

Filed Dec. 6, 1967, Ser. No. 9,669

Term of patent 14 years

(Cl. D26—13)

FIG. 1 is an isometric view of my motion picture projector control;

FIG. 2 is a front elevational view thereof;

FIG. 3 is a side elevational view looking from the right of FIG. 2;

FIG. 4 is a rear view thereof;

FIG. 5 is the opposite side elevational view thereof; and

FIG. 6 is a top plan view thereof.

The dominant features reside in the solid line portions.

I claim:

The ornamental design for a motion picture projector control, as shown and described.
